GAS ANÆSTHETIZER

Orin Harry Peak, Hollywood, Calif.

Application March 19, 1930. Serial No. 437,068

6 Claims. (Cl. 128—203)

This invention relates to anæsthetizing apparatus.

An object of the invention is to provide improvements in existing apparatus of this general class, whereby the safety, surety, facility, and effectiveness of the administration of anæsthetics, are materially enhanced.

A more detailed object is the provision of a relatively simple and easily operable mechanism whereby a gaseous anæsthetic such as nitrous oxide, and a nutrient gas such as oxygen or air, or a mixture thereof, may be administered to a patient in known quantities, and at proper pressure corresponding to lung capacity and pressure, respectively. Such apparatus is used to maintain a patient in a state of full anæsthesia or in a state of analgesia, i. e., a state of unconsciousness sufficiently profound to render the patient insensible to pain, but not so deep that difficulty is apt to be encountered in resuscitating the patient whenever desired.

A further object is to effect improvements in known apparatus used for this purpose, of such a nature that the anæsthetist may readily effect variation in the quantity of either of the gases administered, so as to quickly compensate for any unexpected development tending to affect the depth of the patient's anæsthesia, and to counteract either too great or too little a content of either of the gases in the mixture supplied to the patient.

Another object is to provide a resiliently distensible reservoir which may be filled with a mixture of the gases in proper quantitative relationship, and a similar reservoir for the reception of a quantity of each of the gases in an undiluted condition, each of the reservoirs being of such design that its inherent tendency to collapse, imposes the proper pressure upon the gas so as to insure delivery thereof, to the patient.

A still further object is to provide valve means whereby the delivery tube which communicates with the face mask, and which hence conducts the gases to the patient, may optionally and practically instantaneously be connected to any one of the three reservoirs, and at the same time seal both of the other two reservoirs, so that the gases therein are held available for instant use and at proper pressure to be drawn upon whenever desired.

Yet another object in this connection, is to so simplify the apparatus and especially the control valve therefor, that no especial skill is necessary for its proper manipulation, thus permitting a surgeon or other person conducting an opera-

tion, to personally control the administration of the anæsthetic, and with such ease and surety that his intention need not be unduly distracted from the progress of the operation itself.

A further object is to so arrange the control valve and the parts associated therewith, that the operator is enabled not only to enrich or weaken the gas being supplied to the patient, but also to supply either the nutrient gas or the anæsthetizing gas in pure, concentrated form, and without destroying the setting of the valves maintaining a normal mixture of the gases. Thus, when the emergency requiring the administration of either gas in more concentrated form than normally, is past, the normal mixture may again be instantly supplied.

The invention possesses other objects and advantageous features, some of which, with those enumerated, will be set forth in the following description of the invention's particular embodiment which is illustrated in the drawings accompanying and forming a part of the specification.

Referring to the drawings:

Figure 1 is a front elevation of a piece of anæsthetizing apparatus incorporating the principles of the present invention.

Fig. 2 is a horizontal, compound sectional view, the planes of section being indicated by the lines 2—2 of Fig. 1, and the direction of view by the arrows.

Fig. 3 is a transverse, vertical sectional view taken upon the line 3—3 of Fig. 1, with the direction of view as indicated.

Fig. 4 is an enlarged, detail sectional view taken upon the line 4—4 of Fig. 1, with the direction of view as indicated.

Fig. 5 is a diagrammatic view showing the connections between the various elements of my improved apparatus.

In terms of broad inclusion, the apparatus of the present invention comprises a source of supply of each of a plurality of fluids, a resiliently distensible reservoir associated with each, a delivery tube for conducting gas from the apparatus to a patient, and valve means whereby communication may be established optionally between the patient and any or all of the sources of supply. The valve means is also adapted to automatically establish communication between a source of supply and the reservoir associated therewith whenever that source of supply is connected to the supply tube, and also with another reservoir containing a mixture of the gases, according to predetermined proportion, when the supply tube is connected to both sources of supply.

Specifically describing the invention in its preferred embodiment, the apparatus is preferably supported upon a suitable, portable stand 11 having a base 12, whereby the apparatus may be disposed in any convenient location. The apparatus itself, comprises a centrally located valve housing 13 having a sleeve 14 extending downwards from the bottom thereof, and adapted to be received upon the upper end of the stand 11, to suitably position the device. Arms 16 and 17 extend from opposite sides of the housing 13, to support pressure reducing valves 18 and 19 respectively, of well-known design. Preferably a pair of brackets 21 are associated with each of the reducing valves 18, 19, each of these brackets 21 being adapted to establish communication between the associated reducing valve, and a steel cylinder 22 of the type commonly employed for storage and transportation of gases under high compression. The cylinders 22 connected to the reducing valve 19, should contain a gaseous anesthetic such as nitrous oxide, carbonic acid gas, ethylene, or other similar agents, whereas the cylinders 22 associated with the reducing valve 18, should contain a suitable nutrient gas such as oxygen or air.

The purpose of employing a plurality of cylinders 22, 23, communicating with each of the reducing valves 18, 19, respectively, is to prevent the possibility of completely exhausting the available supply of either gas during the progress of an operation.

Inasmuch as the design of the reducing valves 18, 19, has no bearing upon the present invention, their construction need not be described herein. Suffice it for the purpose of the present disclosure therefore, to explain that both cylinders 22, 23, associated with each reducing valve 18, 19 respectively, are adapted to supply gas thereto at relatively high pressure, and that the reducing valve 18 is provided with preferably a pair of outlets 24 and the other valve 19 having a single outlet 25—each reducing valve being susceptible of adjustment so as to deliver gas at a known reduced pressure by way of each outlet 24.

One of the outlets 24 of the reducing valve 18 communicates through a suitable length of tubing 26 with a needle valve 27 which is mounted upon the arm 16; and from the needle valve 27 a length of tubing 28 communicates with one side 50 of the valve housing or chamber 13. Similarly, the outlet 25 of the reducing valve 19, communicates through a tube 29 with a needle valve 31, and from the needle valve 31 a length of tubing 32 leads to the valve housing 13 at a point closely adjacent that at which the tubing 28 enters thereinto.

A valve 36 is mounted for rotational movement within the valve chamber 13, the engaging faces of the valve 36 and chamber 13 preferably being conical as clearly shown upon Fig. 3, for the purpose of establishing a more efficient joint therebetween. The valve 36 is hollow, and is open at the bottom thereof so that the bore 37 of the valve 36 is at all times in communication with a relatively large opening 38 in the bottom of the chamber 13. A nipple 39 communicates with the opening 38, and is adapted to have mounted thereon a delivery tube 41 which is flexible and which leads to a conventional face mask (not shown) adapted to be engaged upon the face of a patient so as to cause him to breathe gases delivered to him through the delivery tube 41.

The tapering walls 42 of the valve 36, are provided with diametrically opposed openings or ports 43, each of which is relatively large, so as

to permit unrestricted flow of gases therethrough when they are brought into registration with suitable openings in the walls of the chamber 13. The relatively large size of the ports 43 also makes it possible to establish communication between the bore 37 of the valve 36 and both tubes 28 and 32 through one of these ports. Hence, when the valve 36 is positioned to bring one of the ports 43 into registration with the entrance of both tubes 28 and 32 into the chamber 13, both oxygen and N₂O may be delivered to the patient through the delivery tube 41.

Diametrically opposite the area at which the tubes 28 and 32 enter the chamber 13, another opening or port 46 is formed in the wall of the chamber 13. From this opening 46 a relatively large tube 47 extends, the outer end 48 of the tube 47 extending downwards and being adapted to receive the neck of a resiliently distensible reservoir 49. This reservoir 49 is preferably in the form of a rubber bag of capacity materially exceeding maximum lung capacity, so that the reservoir 49 is capable of holding in store, a quantity of gas sufficient to supply a patient when taking the deepest possible breath. The inherent tendency of the reservoir 49 to collapse, which is caused by the elasticity of the material of which it is composed, results in imposing a sufficient amount of pressure upon the gas contained therein, to supply the gas to the patient at approximately lung pressure, i. e., about five pounds per square inch above atmospheric.

Means are also provided for controlling the rate of flow of each of the two gases, so as to keep the reservoir 49 supplied at a rate sufficient to compensate for the rate at which the patient withdraws the mixture of gases from the reservoir 49 during normal respiration. (In the case of an adult person, this rate is approximately 1.5 liters per minute). Each of the tubes 28 and 32 enters the valve chamber 13 through an L-fitting 51 to which the associated tube 28 or 32 is coupled through the expedient of a union 52 of conventional design. The structure of this union is best shown upon Fig. 4, and includes a ferrule 53 threaded onto the outer end of the associated L-fitting 51. The end of the associated tube 28 or 32, as the case might be, extends through a suitable aperture 54 in the outer end of the ferrule 53, and seats within the end of the bore 56 of the L-fitting 51. However, a slight bead 57 is formed on the end of the tube 28 or 32, as the case might be, this bead 57 seating within a counterbored portion 58 of the bore 56. The bead 57 is of greater diameter than the hole 54 in the ferrule 53, through which the tube extends, with the result that when the ferrule 53 is tightened, the bead 57 is crowded tightly into the counterbored portion 58 of the bore 56, to establish an efficiently tight joint between the L-fitting 51 and the tube 28 or 32. This is the construction of a well-known type of union whereby tubing such as the well-known copper tubing may be joined to any desired type of fitting. However, the presence of such a joint in each of the tubes 28 and 32, facilitates the provision of a restriction in each tube, inasmuch as such restriction may easily be formed by filling the extreme end of the tube 28 or 32, as the case may be, with solder 59 or other suitable material, and then drilling a hole 60 of known diameter, through the material disposed within the tube. By this means, restricted orifices 61 and 62 may easily be formed in the tubes 28 and 32 respectively, thus making it possible to control the flow

of gas through each tube 28 and 32, to accurately attain a predetermined rate by manipulating the needle valves 27 and 31 respectively.

Each of the tubes 28 and 32 is provided with a pressure gauge 63, 64 respectively, between the associated needle valve 27 or 31, as the case might be, and the associated orifice 61 or 62, as the case may be. As a result of this arrangement, each needle valve 27, 31 may be manipulated so as to establish a predetermined pressure within the associated tube 28, 32—these pressures being indicated upon the gauges 63 and 64 respectively. Therefore, knowing the pressure behind each orifice 61, 62 and the cross-sectional area of each orifice, the rate of flow may easily be calculated, and each of the needle valves 27 and 31 will be so regulated that the rate of flow of both gases into the valve chamber 13, is sufficient to keep the patient supplied with the proper amount of oxygen and N₂O to insure his being maintained in that state of anesthesia desired.

It should be explained that the face mask, usually employed, is provided with an exhaling valve whereby gases expelled from the patient's lungs, are discharged to the atmosphere instead of being forced back into the anesthetizing apparatus, with the result that there is an intermittent flow in but one direction, through the delivery tube 41. The fact that the resiliently distensible reservoir 49 is in communication with the face mask, compensates for this intermittent flow of the gases from the apparatus to the patient, as a result of his respiration. When the patient is inhaling, the mixture of gases will be supplied to him as a result of the partial collapse of the reservoir 49; and while he is exhaling, the bag 49 will again be filled by the flow of the gases through the tubes 28 and 32, into the valve chamber 13. Consequently, a mixture of the two gases, according to predetermined quantitative relationship, is continually supplied under suitable pressure to the face mask, so that each time the patient inhales, his lungs will be supplied with this mixture of gases.

Attention should be directed to the fact that the outlet opening 38 through which gas flows into the delivery tube 41, and also the opening 46 and tube 47 through which communication is established between the bag 49 and the delivery tube 41, are of relatively large cross-sectional area, making it possible to supply an adequate quantity of gas to the patient even in the event of an extremely rapid inhalation, such for example, as when the patient gasps.

Although manipulation of the needle valves 27 and 31 permits accurate regulation of the richness of the mixture of gases supplied to the patient, so that just the desired degree of anesthesia may be maintained to suit the patient's requirements as determined by the operator, it frequently happens during the course of an operation, that some event transpires which requires a prompt variation in the richness of the mixture. Particularly true is this in the case of oral operations where it is necessary to administer the anesthetic to the patient through the expedient of a mask covering his nose only. When such a mask is used, a patient occasionally inhales through his mouth, or the operator disturbs the mask, permitting the patient to inhale a larger amount of oxygen than he should be allowed to receive, to preserve the desired state of anesthesia. Consequently, I have provided means in my improved anesthetizing apparatus, for instantly increasing the content of

gaseous anesthetic supplied to the delivery tube 41; and inasmuch as it occasionally occurs that too rich a mixture of anesthetic gas is supplied to the patient, I have also provided means for instantly supplying pure oxygen to the delivery tube 41, so as to enable the operator to effect partial or complete resuscitation of the patient whenever occasion demands.

A second tube 66 leads from the needle valve 31 whereby the flow of N₂O from the pressure reducing valve 19 is controlled.

This tube 66 is also provided with a restricted orifice 67 preferably formed in the same manner as the orifices 61 and 62 previously described. Beyond the orifice 67 the tube 66 leads into the valve chamber 13 at a point suitably spaced from the port 46—preferably the angular displacement of the port 68 through which the tube 66 enters the chamber 13 and the port 46 through which communication is established when the reservoir 49 is 60°.

The second resiliently distensible reservoir 69 connects through a relatively large tube 71 with the valve chamber 13, entering thereinto through a port 72 diametrically opposite the port 68, so that when the valve 36 is turned to bring its ports 43 into register with both ports 68 and 72, such positioning of the valve 36 will permit N₂O to flow through the tube 66 into the valve chamber 13 at a rate determined by the cross-sectional area of the orifice 67 and the pressure within the tube 66 as governed by the needle valve 31 and as indicated upon the gauge 64. It should be observed, however, that whenever the port 68 communicates with the interior of the valve chamber 13, the port 72 also communicates therewith so that nitrous oxide is supplied to the patient through the port 38 in the bottom of the valve chamber 13, not only from the tube 66, but also from the reservoir 69 which is of the same construction as the reservoir 49. This makes it possible to sustain the same pressure upon the gases supplied to the patient, and to permit continued respiration even though pure N₂O is being supplied to the patient.

The means for supplying pure oxygen to the patient, is in the form of another tube 76 leading directly from another of the outlets 24 of the reducing valve 18, to a port 77 in the valve chamber 13. Preferably this port 77 is disposed upon the opposite side of the port 46 from the port 68, the port 46 being disposed midway between the ports 68 and 77. The tube 76 is similarly provided with a restricted orifice 78.

Diametrically opposite the port 77, a port 81 is disposed; and through this port 81 a third resiliently distensible reservoir 82 communicates with the valve chamber 13 by means of a relatively large tube 83. Thus it may be seen that pure oxygen may be supplied to the patient by throwing the valve 36 in the direction opposite that which results in supplying the patient with pure N₂O. In other words, when a situation arises during the progress of an operation, which requires that the patient be immediately revived either partially or completely, the operator or the anesthetist, may rotate the valve 36 so as to bring the ports 43 thereof, into register with the ports 77 and 81, whereupon communication will be established between the delivery tube 41, the tube 76, and also the reservoir 82. Since this reservoir 82 is of the same construction as the reservoirs 49 and 69, the same pressure may be maintained within the entire system, causing continued flow of gas to the patient at the same rate, although the apparatus, for instantly increasing the content of

paratus has been so adjusted as to supply pure oxygen to him.

It is to be observed that the tube 76, instead of leading from the needle valve 27, leads directly from the pressure reducing valve 18. The reason for this is that occasion frequently arises requiring the prompt, partial resuscitation of the patient, which may be accomplished by supplying him with a relatively large quantity of pure oxygen. Under some circumstances, the quantity of oxygen required, is considerably greater than that which is used throughout the major portion of the operation, as one of the components of the mixture of gases. Hence, if the tube 76 led from the needle valve 27, it would be necessary to change the adjustment of that valve in order to supply the necessary quantity of oxygen to the patient, to meet such an emergency. However, with the tube 76 arranged as hereinabove described, and by making the restricted orifice 78 of suitable cross-sectional area, it is made possible for the operator to supply the patient instantly, with a greatly increased quantity of oxygen without the necessity of disturbing the setting of the needle valve 27.

The valve 36 is mounted for rotational adjustment within a valve chamber 13, by means of a cover plate 86 which is rigidly secured across the top of the valve chamber 38 by means of a plurality of screws 87 or their equivalent. The valve 36 carries a stem 88 which is rigid therewith, and which extends rotatably through the plate 86, an operating handle 89 being rigidly secured to the stem 88 above the plate 86. Preferably a coil spring 91 is interposed between the plate 86 and the top 92 of the valve 36, this spring serving to continually press the valve 36 downwards so as to establish a tight seal between it and the tapering walls of the valve chamber 13. Preferably three bosses 93 are formed upon the upper face of the plate 86. A pointer 94 registers with the central one of these bosses 93 when the ports 43 of the valve are in register with the ports 46, and with the entrances of the tubes 28 and 32 into the valve chamber. The other two of these bosses 93 are adapted to be engaged by some portion of the handle 89, and limit movement thereof, beyond those positions in which pure oxygen and pure nitrous oxide are supplied to the valve chamber.

Preferably three bosses 93 are formed upon the upper face of the plate 86. A pointer 94 registers with the central one of these bosses 93 when the ports 43 of the valve are in register with the ports 46, and with the entrances of the tubes 28 and 32 into the valve chamber. The other two of these bosses 93 are adapted to be engaged by some portion of the handle 89, and limit movement thereof, beyond those positions in which pure oxygen and pure nitrous oxide are supplied to the valve chamber.

Operation

The anæsthetist first determines the richness of the anæsthetic gas which is to be supplied to the patient, and then sets the needle valves 27 and 31 so that proper pressures are attained in the tubes or bypasses 28 and 32 respectively, whereby suitable quantities of oxygen and nitrous oxide are forced through the orifices 61 and 62 respectively, so as to attain that predetermined mixture of the gases.

This mixture of gases of oxygen and nitrous oxide may be supplied both to the patient and to the resilient reservoir 49, by positioning the pointer 94 of the handle 89, in register with the central boss 93, this being the position of the valve and handle shown upon Figs. 2, 3, and 5. As explained hereinabove, the inherent tendency of the reservoir 49 to collapse, maintains a suitable pressure upon the gas supplied to the patient, in spite of the fact that the patient withdraws the gas therefrom in an intermittent flow as determined by the rapidity of his respiration. As will be well understood, supplying the mixture of oxygen and nitrous oxide to the patient in this

manner, will effect anæsthesia. Should it eventuate however, that during the course of the operation, the face mask becomes disturbed or the patient is permitted to breathe a quantity of air which causes his partial resuscitation, the operator or the anæsthetist will be able to detect such change in the patient's condition; and by throwing the handle 89 of the valve toward that side of the apparatus with which the cylinders 23 containing nitrous oxide are associated, he may cause pure N₂O to be supplied to the patient. As will be readily appreciated, this adjustment of the apparatus may be effected almost instantaneously, whereby any change in the profundity of the patient's anæsthesia, may quickly be compensated for.

Similarly, should it develop that the patient starts to go too deeply under the influence of the anæsthetic, he may be promptly revived either partially or completely, according to the will of the operator, by throwing the handle 89 in the opposite direction, whereupon pure oxygen may be supplied to the patient, in an increased quantity.

An important feature of the apparatus of the present invention, lies in the fact that whenever the valve 36 is moved from one position to another, the reservoir 49, 69, or 82, as the case may be, from communication with which the valve is moved, is sealed off tightly, with the result that a suitable quantity of gas is retained therein at lung pressure, so that it is available for subsequent instant use when occasion therefor arises. Consequently, whenever the valve 36 is moved to establish communication between the patient and any one of the reservoirs 49, 69, or 82, the selected gas or mixture of gases starts to flow to the patient instantaneously, and at lung pressure, so that the effect upon the patient of the alteration of the composition of the gas supplied to him, is practically instantaneous.

Thus it may be seen that the patient's condition may be held under absolute control and with the expenditure of such a small amount of mental or physical effort on the part of the operator, that his attention need be distracted very little from the progress of the operation itself. If the change in the patient's condition is so slight that only a very small adjustment of the richness of the anæsthetic gas will compensate therefor, the operator may easily and promptly take care of the situation by throwing the handle 89 to the proper side so as to effect admission of pure oxygen or pure N₂O according to the circumstances, and then immediately throwing handle 89 back to an intermediate position. Inasmuch as both oxygen and nitrous oxide are held in readiness for immediate withdrawal, a sufficient quantity of the selected gas will be supplied to the patient, to effect a material alteration of the depth of his anæsthesia, even though communication is established between the patient and the reservoirs 69 or 82, containing the selected gas, for only a very short space of time.

It is to be understood that the details of the invention as herein disclosed, are subject to alteration within the spirit or scope of the appended claims.

I claim:

1. In an anæsthetizing apparatus, a source of supply of a nutrient gas, a source of supply of an anæsthetic gas, a valve chamber, a valve movable therein having inlet ports and an outlet port communicating with each other, a delivery tube communicating with said outlet port, a supply tube

- leading from each of said sources of supply to said valve chamber, a resiliently distensible reservoir adapted to be connected to each of said supply tubes, both of said reservoirs communicating separately with said valve chamber at points equally spaced from the entrances of their respective supply tubes into said valve chamber, and said inlet ports being separated a distance on said valve corresponding to the spacing between respective 5 points of entry of a reservoir and its respective supply tube into said chamber whereby the valve may be moved to establish communication optionally between said outlet port and either inlet port and its respective reservoir.
- 10 2. In an anæsthetizing apparatus, a source of supply of a nutrient gas, a source of supply of an anæsthetic gas, a valve chamber, a valve movable therein having oppositely disposed inlet ports and an outlet port, all of said ports being in communication with each other, a delivery tube leading from said valve chamber and communicating with said outlet port, a supply tube leading from each of said sources of supply into said valve chamber, a resiliently distensible reservoir adapted to be connected to each of said supply tubes by said valve chamber at a point opposite that at which its respective supply tube enters said valve chamber, a third resiliently distensible reservoir communicating with said chamber, and bypasses from both of said supply tubes entering said valve chamber at a common location opposite that at which said third reservoir communicates therewith.
- 15 3. In an anæsthetizing apparatus, a source of supply of a nutrient gas, a source of supply of an anæsthetic gas, a valve chamber, a valve movable therein having oppositely disposed inlet ports and an outlet port, all of said ports being in communication with each other, a delivery tube leading from said valve chamber and communicating with said outlet port, a supply tube leading from each of said sources of supply into said valve chamber, a pair of resiliently distensible reservoirs adapted to be connected to each 20 of said supply tubes by said valve chamber at a point opposite that at which its respective supply tube enters the valve chamber, a third resiliently distensible reservoir communicating with said valve chamber at a point situated between the entrances of said supply tubes thereinto, and bypasses from both of said supply tubes entering said valve chamber at a common location opposite that at which said third reservoir communicates therewith.
- 25 4. In an anæsthetizing apparatus, a source of supply of a nutrient gas, a source of supply of an anæsthetic gas, a valve chamber, a valve movable therein having oppositely disposed inlet ports and an outlet port, all of said ports being in communication with each other, a delivery tube leading from said valve chamber and communicating with said outlet port, a supply tube leading from each of said sources of supply into said valve chamber at a point opposite that at which its respective supply tube enters the valve chamber, a third resiliently distensible reservoir communicating with said valve chamber at a point opposite that at which said third reservoir communicates therewith.
- 30 5. An anæsthetizing apparatus comprising a source of supply of oxygen, a source of supply of nitrous oxide, a valve chamber, a supply tube each for said sources of supply and leading to the valve chamber, each supply tube having a bypass leading to the valve chamber, three resiliently distensible reservoirs, the first for oxygen, the second for nitrous oxide, and the third 35 for a mixture of said two gases, each of said reservoirs having a conduit leading to the valve chamber, a valve member controlling communication optionally between the valve chamber and one of said straight gas reservoirs and its respective supply tube while closing the other supply tube, the other two reservoirs, and both the bypasses, or establishing a communication between the valve chamber and both the bypasses and the mixed gas reservoir while closing communication between the valve chamber and both the supply tubes and both straight gas reservoirs, and a delivery tube leading from the valve chamber.
- 40 6. An anæsthetizing apparatus comprising a source of supply of oxygen, a source of supply of nitrous oxide, a valve chamber, a supply tube each for said sources of supply and leading to the valve chamber, each supply tube having a bypass leading to the valve chamber, three resiliently distensible reservoirs, the first for oxygen, the second for nitrous oxide, and the third for a mixture of said two gases, each reservoir having a conduit leading to the valve chamber, a rotatable valve member located within the valve 45 chamber and having ports so spaced that communication may be established optionally between the valve chamber and one of said straight gas reservoirs and its respective supply tube while closing communication with the other supply tube, the other two reservoirs, and the bypasses, or establishing communication between the valve chamber and both bypasses and the third reservoir while closing communication with the first and second reservoirs and both supply tubes, and a delivery tube leading from the valve chamber.

ORIN HARRY PEAK.
